(57) **CLAIM**

I claim the ornamental design for modular children's furniture set, as shown and described.

DESCRIPTION

FIG. 1 is a view from the top right, of modular children's furniture set arranged in a first configuration showing my new design;

FIG. 2 is a front elevation view of the modular children's furniture set arranged in a first configuration;

FIG. 3 is a rear elevation view of the modular children's furniture set arranged in a first configuration;

FIG. 4 is a right side; elevation view of the modular children's furniture set arranged in a first configuration;

FIG. 5 is a left side elevation view of the modular children's furniture set arranged in a first configuration;

FIG. 6 is a top plan view of the modular children's furniture set arranged in a first configuration;

FIG. 7 is a bottom plan view of the modular children's furniture set arranged in a first configuration;

FIG. 8 is an exploded view from the top right of the modular children's furniture set showing all the components separated;

FIG. 9 is a view from the top right of the modular children's furniture set arranged in a second alternate configuration;

FIG. 10 is a view from the top right of the modular children's furniture set arranged in a third alternate configuration;

FIG. 11 is a view from the top right of the modular children's furniture set arranged in a fourth alternate configuration;

FIG. 12 is a view from the top right of the modular children's furniture set arranged in a fifth alternate configuration;

FIG. 13 is a view from the top right of the modular children's furniture set arranged in a sixth alternate configuration;

FIG. 14 is a view from the top right of the modular children's furniture set arranged in a seventh alternate configuration;

(Continued)

FIG. 15 is a view from the top right of the modular children's furniture set arranged in an eighth alternate configuration;

FIG. 16 is a view from the top right of the modular children's furniture set arranged in a ninth alternate configuration;

FIG. 17 is a view from the top right of the modular children's furniture set arranged in a tenth alternate configuration;

FIG. 18 is a view from the top right of the modular children's furniture set arranged in an eleventh alternate configuration;

FIG. 19 is a view from the top right of the modular children's furniture set arranged in a twelfth alternate configuration;

FIG. 20 is a view from the top right of the modular children's furniture set arranged in a thirteenth alternate configuration;

FIG. 21 is a view from the top right of the modular children's furniture set arranged in a fourteenth alternate configuration;

FIG. 22 is a view from the top right of the modular children's furniture set arranged in a fifteenth alternate configuration;

FIG. 23 is a view from the top right of the modular children's furniture set arranged in a sixteenth alternate configuration;

FIG. 24 is a view from the top right of the modular children's furniture set arranged in a seventeenth alternate configuration; and,

FIG. 25 is a view from the top right of the modular children's furniture set arranged in an eighteenth alternate configuration.

The evenly broken lines in FIG. 8 depict environmental subject matter, while the long dash/short dash lines indicate the separated components in an exploded view of FIG. 8 and all broken lines form no part of the claimed design.

The claim is directed to the collective appearance of the set of modular children's furniture components arranged as shown in the figures.

1 Claim, 25 Drawing Sheets
